US00D844654S

(12) **United States Design Patent** (10) **Patent No.:** **US D844,654 S**
(45) **Date of Patent:** **** Apr. 2, 2019**

(54) **DISPLAY SCREEN OR PORTION THEREOF
WITH GRAPHICAL USER INTERFACE**

- (71) Applicant: **Apple Inc.**, Cupertino, CA (US)
(72) Inventors: **Alan C. Dye**, San Francisco, CA (US);
Christopher Foss, San Francisco, CA (US); **Wan Si Wan**, Sunnyvale, CA (US); **Christopher Wilson**, San Francisco, CA (US)
(73) Assignee: **Apple Inc.**, Cupertino, CA (US)
(**) Term: **15 Years**
(21) Appl. No.: **29/628,334**
(22) Filed: **Dec. 4, 2017**

Related U.S. Application Data

- (63) Continuation of application No. 29/604,007, filed on May 15, 2017, now Pat. No. Des. 804,516, which is a continuation of application No. 29/560,677, filed on Apr. 8, 2016, now Pat. No. Des. 786,913, which is a continuation of application No. 29/501,088, filed on Sep. 1, 2014, now Pat. No. Des. 753,711.

CLAIM

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

The FIGURE is a front view of a display screen or portion thereof with graphical user interface showing the claimed design.

The broken lines in the FIGURE show a display screen or portion thereof, and form no part of the claimed design.
